UNITED STATES PATENT OFFICE.

WILLIAM B. DURGIN, OF CONCORD, NEW HAMPSHIRE.

DESIGN FOR A HANDLE FOR TABLE-WARE.

SPECIFICATION forming part of Design No. 13,983, dated June 19, 1883.

Application filed April 4, 1883. Term of patent 3½ years.

To all whom it may concern:

Be it known that I, WILLIAM B. DURGIN, a citizen of the United States, residing at Concord, county of Merrimac, and State of New Hampshire, have invented and produced a new and original Design for a Handle for Table-Ware, of which the following is a specification, reference being had to the accompanying drawings, forming part of this specification.

10 My improved design relates, mainly, to a handle for table-ware, and is shown in this instance embodied in a spoon.

Figure 1 is a front view, and Fig. 2 a side view, of a spoon made in accordance with my 15 improved design.

The design relates especially to the handle, which is made to represent a rush or cat's-tail. The said handle consists, mainly, of a long cylindrical stem portion, *a*, surmounted by a cylindrical portion, *b*, of larger diameter, having a smaller projection or knob, *c*, at its end, the 20 said cylindrical portion *b* being rounded at its ends, as shown at 2, and made with a dull surface, closely resembling the well-known cat's-tail reed. As shown in this instance, the han- 25

dle *a b c* is used for a spoon, the bowl *d* of which is made to represent a leaf having its stem *e* twined around the lower end of the stem portion *a* of the handle.

I claim—

1. The herein-described design for a handle for table-ware, consisting of the stem *a* and cylindrical projection *b*, representing a cat's-tail reed. 30
2. The handle *a* and cylindrical projection *b*, having rounded ends and the knob *c*, the said projection *b* having a dull surface, as described. 35
3. The handle consisting of the stem *a* and cylindrical projection *b*, having a dull surface, and the bowl *d*, made as a leaf having its stem twined around the stem portion *a* of the handle. 40

In testimony whereof I have signed my name to this specification in the presence of two sub- 45 scribing witnesses.

WM. B. DURGIN.
